UNITED STATES PATENT OFFICE

EDWARD C. EKSTROMER, OF SAN FRANCISCO, CALIFORNIA, ASSIGNOR, BY DIRECT AND MESNE ASSIGNMENTS, OF ONE-HALF TO JAMES F. GALLAGHER, OF BOSTON, MASSACHUSETTS, AND ONE-HALF TO THE EDWARD C. EKSTROMER CORPORATION, OF RENO, NEVADA, A CORPORATION OF NEVADA

PNEUMATIC MOTOR FOR OIL-WELL PUMPS

Application filed March 21, 1928. Serial No. 263,412.

My present invention relates to oil well pumping apparatus and a method of operating the same and more particularly to an improved form of fluid pressure apparatus.

5 An object of my invention is to provide an improved prime mover for oil well pumps which can be lowered into the well with the pump.

Another object of my invention is to provide an improved type of fluid pressure motor for oil well pumps and the like which can be assembled in various numbers so as to produce a power unit of any desired capacity while at the same time not enlarging the 10 diametrical dimension to the end that, irrespective of power capacity, it will always fit within the well casing.

15 A further object of my invention is to provide a pneumatic motive power unit for oil well pumps and a method of operating the same whereby the natural gas from the well can be utilized under pressure as the operating fluid.

20 Other objects and advantageous features, some of which with the foregoing, will be set forth at length in the following description wherein I have outlined in full that form of apparatus which I have selected for illustration in the drawings accompanying and 25 forming a part of this specification.

At the present time oil well pumps of the reciprocating type are operated by means of a motive power unit located on the surface 30 at the top of the well. These units comprise a prime mover, a walking beam which is oscillated by means of a pitman connected to the prime mover and a sucker rod which is attached to the walking beam and caused to move with a reciprocating movement as the walking beam is oscillated. The sucker rod 35 extends downwardly into the well where it connects to the moving parts of the pump. The use of such a sucker rod is attendant with many undesirable features, some of which are: stretching, whipping, and its weight. All of these undesirable features become more exaggerated as the depth of the well increases and it is therefore desirable 40 that some means be provided whereby these difficulties can be overcome.

In order to overcome these difficulties, I propose to construct a prime mover element for operating a reciprocating oil well pump which can be lowered into the well and which will dispense with the use of the above-referred-to motive power means and its co-operating sucker rod. The greatest obstacle in providing such a unit is in providing a unit small enough to be inserted into the well casing, which casing is of relatively small 55 diameter for such a purpose. This restriction in the size of such a unit, however, applies only to its horizontal or diametrical dimensions and since it can be made of almost any desired length, I propose to build a fluid pressure mechanical power unit by employing a plurality of smaller power units, each of which is small enough to be inserted in the well. These units are then connected mechanically together through a suitable piston 60 rod which is adapted to be connected with the sucker rod of a pump which will be secured to the lower end of the motive power 65 unit.

A further feature of my invention is the 70 manner of operating these pneumatic mechanical power units. It is essential that no explosive mixtures be produced within the well because of danger of explosions and since the use of compressed air would introduce oxygen into the well and thus form an explosive mixture, I propose to overcome 75 this difficulty and make my device safe by utilizing the gas given off from the wells. In the past this gas has been used for raising 80 oil by the so-called gas lift. This method of applying the gas to this problem is very wasteful of the gas. In accordance with my invention the gas is collected in gasometers and compressed as is now commonly done 85 where gas lifts are in operation. The gas is then stored in tanks under pressure from which it is conducted to the pneumatic power units by means of a suitable pipe which will extend downwardly into the well along 90 side of the usual oil well discharge pipe.

For a better understanding of my invention, reference should be had to the accompanying drawings, in which I have shown 95 by way of illustration and not of limitation 100

apparatus which represents the best embodiment of my device now known to me. I desire to have it understood, however, that many changes and modifications can be made 5 therein without departing from the spirit of my invention.

In these drawings:

Fig. 1 is a view in elevation showing a power unit built in accordance with my invention as it appears when lowered into the well 10 casing,

Fig. 2 is an enlarged view in section showing the details of construction of my device, and

Figs. 3, 4, 5, and 6 are horizontal sectional views looking downwardly in the direction of arrows and taken respectively on the lines 15 III—III, IV—IV, V—V, and VI—VI of Fig. 2.

In Fig. 1 of the drawing, 10 designates 20 a well casing such as is commonly inserted into the well bore and 11 designates the usual oil discharge pipe through which the oil is pumped from the bottom of the well. Attached to the lower end of the discharge pipe 11, I provide a flanged coupling member 12 to which I secure fluid pressure motive power units 13 constructed in accordance with my invention, as will hereinafter appear. At 25 the lower end of the unit or units 13, as the case may be, I attach a second flanged member 14. The flanged member 14 is provided with a conduit extending axially therethrough and is provided with means at its 30 lower end whereby a reciprocating pump 15 can be attached thereto.

In this figure of the drawing I show three motive power units connected in series, but it should be understood that any number of 40 such units can be used, as determined by the power or pumping capacity desired. In order to facilitate assembly of these units and provide cylinder heads therefor, I insert between adjacent units a partitioning disc 16 having suitable passageways for the oil and 45 operating valve and piston rods therethrough.

By referring to Fig. 2 it will be seen that the flanged member 12 is provided with a 50 port 17 which connects with the discharge pipe 11. This member is also provided with suitable opening and aligning ports to which pipes 18 and 19 are attached for the purpose of conducting fluid under pressure respectively to and from said motive power unit. The units 13 comprise a body member 20 having a central bore 21, within which a suitable piston 22 reciprocates. The bore 21 is provided at its ends with suitable port openings 55 which connect with ports of an ordinary slide valve 23 for the purpose of admitting fluid under pressure into the cylinder 21 where it functions to move the piston as determined by the position of the slide valve 23. The valve 60 65 65 operates within a pressure chamber 24

formed in the body member 20 and which connects with the fluid pressure inlet pipe 18 and an exhaust port 25 is provided on the opposite side of the valve 23 which connects with the exhaust pipe 19 previously referred to. The valves 23, where a number of valves is used, are all connected to a common valve rod 26 which extends downwardly through the units and is connected at its lower end to a valve operating mechanism to be hereinafter described. Oppositely disposed from the valve chamber 25 I provide a conduit 27 which connects with the conduit 17 of the flanged member 12 through which the oil being pumped will flow to the 80 discharge pipe 11.

While it may be feasible to operate a pump with a single motive power unit as described above, it is believed that a greater number will be necessary in most cases. In order, 85 therefore, to facilitate assembly of several of these units in cooperating relation, I propose to provide the discs 16 previously referred to, which discs will not only simplify the assembly of the parts but will also function as a cylinder head for the cylindrical bores 21. These discs 16 are provided with suitable openings which align co-axially with the above referred to ports and chambers so that passageways are established 90 throughout the assembled unit. The central opening of the disc 16 provides an opening through which a suitable piston rod 28 can operate and it is, therefore, provided with a suitable packing or stuffing box so that the 95 piston may slide freely therethrough without leakage of fluid under pressure. The number of these discs required will be determined by the number of individual units 13 used. At the lower end of the assembled 100 units I provide a disc 29 which is similar to the above discs 16 except that only the oil passageway port is maintained open therethrough. At the point where the valve operating rod 24 extends through this latter disc, 105 I provide a second stuffing box or packing. Attached to the underside of the disc 29 I provide a flanged pump supporting member 30 to the lower end of which the pump 15 is attached. The member 30 is provided with 110 an oil conduit 31 which connects with the discharge end of the pump 15. The pump supporting member is also provided with suitable bearings 32 upon which is mounted 115 a forked valve operating lever 33. It is also provided with a piston rod guide 34 at the lower end thereof having a suitable packing to prevent the escape of oil from the pump. Below the motive power units and within the 120 space provided in the member 30, the piston rod is provided with suitable abutments 35 and 36, adapted to engage the forked ends of the lever 33 so as to move the valves 23 and change the direction of fluid flow therein to thus produce a reciprocating movement of 125 130

the pistons 22, as will hereinafter appear in a description of the operation of my device.

By referring to Fig. 3 it will be seen that the flanged member 12 is so constructed that the discharge pipe 11 will be located centrally thereof to the end that, as the discharge pipe 11 is lowered into the well casing 10, the motive power units 13 will be lowered centrally of the casing without danger of jamming. This view of the drawing also shows the general arrangement of the inlet and exhaust conduits 18 and 19.

By referring to Figs. 4 and 5, it will be seen that the oil discharge conduit 27 extends substantially half way around the cylinder 21 and provides a relatively large conduit through which the oil can flow. This conduit might be extended around the cylinder 21 a greater distance to a point where it would meet the valve chamber 24, but in the drawing it is only shown of a cross section substantially equal to that of the discharge pipe 11. The space between the port 27 and the valve chamber 25 is shown, in these figures of the drawing, depressed to the cylinder wall for the purpose of reducing the weight of the body member 20. In Fig. 4 it will be seen that the exhaust chamber 25 connects with a vertical conduit 37 extending axially through the units 13 and connecting with the exhaust pipe 19. This figure of the drawing also shows a removable cover 38 adjacent the valve chamber which I have provided and which can be readily removed to facilitate adjustment of the valve 23.

In Fig. 6 it will be seen that the pump supporting member 30 is also provided with a semicircular opening which forms the conduit 31. At the lower end of this conduit the member 30 is shaped to form a coupling means whereby the pump can be attached to the lower end thereof with its outlet in communication with the discharge pipe 11 via the conduits 31, 27, and 17. This figure of the drawing also shows one method of mounting the valve actuating lever 33 so that its forked end is held in cooperative relation with the abutments 35 and 36 on the piston rod 28.

The operation of my invention is as follows: After the required number of units 13 has been assembled and the pump 15 attached as is illustrated in Fig. 1, the whole assembly is secured to the end of the discharge pipe 11, the inlet and exhaust pipes 18 and 19 having been previously connected, and is then lowered into the well to a point where the whole unit is submerged in oil. After the pump is properly located within the well, suitable connections are made between the inlet pipe and a source of fluid pressure. This pressure will be transmitted through the inlet pipe to the cylinders 21 and cause the pistons 22 to operate in one direction or the other as determined by the position of the valves 23 and

thereafter as the pistons reciprocate from one extreme of the stroke to the other, the abutments 35 and 36 will engage the forked lever 33 and change the setting of the valve 23 periodically so as to produce a reciprocating movement of the pump.

In order to avoid the accumulation of explosive admixtures within the well, I propose to use natural oil well gas as a pressure fluid by compressing the gas at the surface of the well as is now commonly practiced in operating the so-called gas lift. In other respects my device will operate substantially the same as would a compressed air unit. The use of air, however, in an oil well would, as previously stated, create a hazard as it might introduce oxygen into the well and thus form an explosive mixture, whereas with oil well gas there is no such danger.

While I have shown the preferred form of my invention as now known to me, it is to be understood that various changes may be made in its construction without departing from the spirit of the invention as defined in the appended claims.

Having thus described my invention, what I claim and desire to secure by Letters Patent is—

1. A fluid pressure drive for oil well pumps comprising a plurality of separable units forming an enclosing housing secured to the end of the oil discharge pipe of the well and adapted to be lowered into the well thereby, a reciprocating pump secured to the bottom of said housing, a fluid passageway through each of said units and the housing so formed thereby for connecting said pump and said discharge pipe, each of said units having a double acting fluid pressure motor contained within itself and adapted to be arranged in alignment, means for connecting the piston rods of each of said fluid pressure motors together, and a valve rod for simultaneously controlling the admission of fluid pressure to and from said motors, whereby they will operate in unison to drive said reciprocating pump.

2. A fluid pressure drive for oil well pumps comprising a plurality of separable cylinders having cooperating pistons therein, a piston rod connecting said pistons adapted to connect with and operate a pump, valves for controlling the inlet and exhaust of fluid under pressure to and from each of said cylinders, and a valve rod common to all of said valves adapted to be operated by movement of said piston rod to simultaneously operate the valves, whereby said pistons will operate in unison to drive said pump.

3. A fluid pressure driving means for oil well pumps adapted to be lowered into a well by means of attachment with the end of the oil discharge pipe comprising a body member, a cylinder disposed axially within said body

member, a piston cooperating with said cylinder to produce mechanical movement upon the admission of fluid pressure to said cylinder, a valve for controlling the admission of said fluid, a pump mounted upon the lower end of said body member adapted to be operated by movement of said piston, and a port extending through said body member connecting the discharge pipe with the pump, whereby the output of the pump will be discharged at the top of the well.

4. A pneumatic motor for oil well pumps comprising a plurality of housings adapted to be secured together end to end and lowered into the well at the end of a discharge pipe, said housings having a conduit extending therethrough communicating with said discharge pipe, a pump secured to the lower end of said housings having its outlet communicating with the conduit through said housings, cylinders and co-operating pistons arranged within said housings having a common piston rod, said pistons being connected to said pump through said piston rod, a valve for each of said cylinders, and means controlled by movement of said piston rod adapted to simultaneously operate said valves for controlling the admission and exhaust of fluid under pressure to and from each of said cylinders.

5. A fluid pressure drive means for oil well pumps comprising a plurality of separable fluid pressure motors, each having a cylinder, a piston and a co-operating valve mechanism, characterized by the fact that the cylinders and valve mechanism of said motors are complementary so that any number of said motors may be assembled together to provide the required amount of power, the cylinders and their respective pistons and valve mechanism of each motor being all adapted to co-operate to produce a simultaneous application of power by each of said motors upon the pump in each direction of its movement.

45 EDWARD C. EKSTROMER.
